UNITED STATES PATENT OFFICE.

CONSTANTINE BOURDUNIS, OF CHICAGO, ILLINOIS.

SHOE-SHINING CHAIR.

Application filed July 25, 1923. Serial No. 653,809.

To all whom it may concern:

Be it known that I, CONSTANTINE BOURDUNIS, a citizen of the United States, residing at Chicago, in the county of Cook and State of Illinois, have invented new and useful Improvements in Shoe-Shining Chairs, of which the following is a specification.

This invention relates to a chair, and an object of the invention is to provide a chair or stand particularly designed for use in shoe shining parlors, and one which may be manufactured at a relatively low cost and which will be neat and artistic in appearance.

Another object of this invention is to provide a chair or stand structure as specified in which the foot rests are normally held in rearward position beneath the seat of the chair so as to permit a patron to easily seat himself in the chair without interference of the foot rests, and which foot rests are adapted to be moved outwardly and held in proper adjusted position after the patron has been properly seated.

Other objects of the invention will appear in the following detailed description taken in connection with the accompanying drawings wherein:

Fig. 1 is a front elevation of the improved shoe shining chair.

Fig. 2 is a vertical section through the chair.

Fig. 3 is a transverse vertical section through a part of the chair structure taken on the line 3—3 of Fig. 2.

Fig. 4 is an enlarged fragmentary plan of a part of the seat structure.

Fig. 5 is a detail section taken on the line 5—5 of Fig. 2.

Fig. 6 is a section taken on the line 6—6 of Fig. 2.

Fig. 7 is a detail section through a part of the chair structure.

Referring more particularly to the drawings, the improved chair comprises a pedestal 1 which is hollow, and has a supporting base 2. The upper end of the pedestal 1 is open, and receives therein the depending connecting flange 3 formed centrally on the under surface of the seat structure 4. The seat structure 4, as clearly shown in Fig. 2 of the drawings is formed of a casting frame structure, upon which a cushion 5 of any approved construction rests. The cushion 5 is removable. The chair has a back struc-

ture which includes posts 6 that are attached to the seat frame 4 and to the back housing shell 7. The cushion 8 of any approved type is mounted in the shell 7 and is attached thereto preferably by bolts or the like 9. Handles or arm rests 10 are formed on the shell 7 and project forwardly therefrom having their outer ends supported by suitable posts 11.

The pedestal 1 has a bracket structure 12 attached thereto. The bracket structure 12 is also attached to the base 2, as clearly shown in Figs. 1 and 2 of the drawings and supports a housing 13 in which a drawer 14 is slidably mounted. The drawer 14 preferably has grooved rollers 15 carried by its bottom which ride over guiding rails 16 carried by the inner surface of the bottom of the housing 13. The drawer 14 has partitions 17 therein which divide its interior into a plurality of compartments adapted to contain the brushes, cloths, polish and other material used in shining shoes.

A pair of rods 18 and 19 are disposed at each side of the housing 13 and they are supported by suitable brackets 20 and 21. Foot rests 22 are provided, the lower ends of which are bent transversely and downwardly, and carry sleeves 23 which slidably engage over the rods 18 and 19 to permit adjustment or sliding movement of the foot rests 22 along the rods. The foot rests 22 have flexible connectors 24 connected thereto which are in turn connected to spools 25 which carry coil springs 26. The coil springs 26 are connected to the spools 25 as shown at 27, so as to rotate the spools for winding the flexible connectors 24 thereon to move the foot rest 22 inwardly beneath the seat structure 4, as shown in Fig. 2 of the drawings. When it is desired to use the foot rests, they are drawn outwardly, unwinding the connectors 24 from the spools and tensioning the springs 26. The upper sleeves 23 have dogs or ear projections 28 formed thereon which are adapted to be engaged by the bills 29 formed on the pivoted levers 30. The levers 30 are detachably carried by the brackets 20, and are urged into engaging position relative to the ears 28 by means of springs 31. The levers 30 engaging the ears 28 will hold the foot rests 22 outwardly in foot supporting positions and when it is desired to release the foot rests, or after the patron's shoes have been shined the levers 30 are rocked by the thumbs of

the operator so as to disengage the bills 29 and ears 28 which permits the springs 26 to wind upon the spools and move the foot rests 22 back to their normal positions.

5 An apron 33 is attached to the front side of the chair bottom frame 4 and extends downwardly and is attached to the upper surface of the housing 13. If it is so desired a mat 34 of any approved type may 10 be mounted upon the top of the housing 13.

It is, of course, to be understood that the invention may be constructed in other manners and the parts associated in different relations and, therefore, I do not desire to be 15 limited in any manner except as set forth in the claims hereunto appended.

Having thus described my invention what I claim is:—

1. A shoe-shining chair comprising a pedestal, a housing carried by said pedestal adjacent its lower end, a pair of shoe shining stands slidably carried by said housing, means for urging and releasably retaining said foot rests in position adjacent to said pedestal.

2. A shoe-shining chair comprising a pedestal, a housing carried by said pedestal adjacent its lower end, a pair of shoe shining stands slidably carried by said housing, means for urging and releasably retaining said foot rests in position adjacent to said pedestal, and means carried by said housing for holding said foot rests in extended positions relative to the pedestal.

25 In testimony whereof I affix my signature.

CONSTANTINE BOURDUNIS.
